UNITED STATES PATENT OFFICE

2,233,553

STEAM GENERATOR

Brace Alden Phillips, Chicago, Ill.

Application March 8, 1938, Serial No. 194,649

1 Claim. (Cl. 122—52)

This invention relates to new and useful improvements in steam generators.

One object of my invention is to provide a steam generator, consisting of three separate units, namely, the upper and lower fire tube boilers and the fire box which is arranged in front of the lower boiler and may be used as an auxiliary boiler.

A further object of my invention is to provide a steam generator of the character specified, capable of generating the maximum amount of steam and heat with the minimum quantity of fuel consumption.

Another object of my invention is to provide a steam generator that is comparatively simple and economical in construction, and is also very compact and may, consequently, be installed in a relatively small space.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a side elevation of a steam generator, embodying my improvements.

Figure 2 is a central longitudinal section of the device.

Figure 3 is a front end view.

Figure 4 is a vertical transverse section, taken through the upper and lower fire tube boilers.

Figure 5 is a horizontal section, taken through the fire box and Figure 6 is a front elevation of the water heater.

Referring to the drawings for a more particular description of my invention, and in which drawings like parts are designated by like reference characters throughout the several views, A designates the fire box, which may also be used as an auxiliary boiler and B and C the upper and lower fire tube boilers, respectively.

The lower fire tube boiler C is supported at the front on the longitudinally disposed brick walls 1, by the outwardly extending heads of flanges 2. The rear ends of the upper and lower boilers extend through the vertical plate 3 and are fastened in place by the radial lugs or ears 4. The plate 3 is provided with the oval casing 5, which surrounds the rear ends of the boilers B and C, and this casing is equipped with the

upper and lower circular doors 6 and 7, respectively, to facilitate repairs or permit the ready removal of the fire tubes 8 and 9, if necessary.

The fire box A is mounted on the floor a suitable distance in front of the lower boiler C. This unit is preferably constructed entirely of steel welded at all joints, and comprises the inner and outer walls 10 and 11, spaced apart at the ends, front and back for the purpose of allowing a free circulation of water around the inner wall 10 as a protection against the heat of the fire box. This space remains filled with water at all times while the generator is in operation and being situated much lower than the upper boiler B, all steam generated in this space will pass via the steam pipe 12 to the top of the boiler B. The pipe 12 is connected to the pipe 13, which leads from the bottom of the water fire box to the steam chamber of the upper boiler. The fire box A is divided into the upper and lower combustion chambers 14 and 15 by the hollow water tube grates 16, which are inclined upwardly and rearwardly to allow any steam generated therein to escape; this overcomes the usual pounding and cracking noise when first starting a fire. The water tube grates 16 are securely welded at opposite ends to the inner wall 10 at the front and back of the fire box. The opening 18 through the upper or top water space is designed as a sight opening and to facilitate any repairs that may be needed to the inside of the upper combustion chamber 14. The grate bars 19 of the lower combustion chamber 15 are preferably made of solid cast iron. The fire box may be easily removed to facilitate repairs to the front end of the boiler C, by disconnecting the steam and water supply pipes. The ash pit 20 of the fire box A extends below the floor level and is of sufficient depth to hold several days accumulation of ashes. The front end of the ash pit is provided with the hinged lid 21, which may be readily raised to permit the removal of the ashes. The lid 21 is provided with an opening 22 covered by a sliding check.

The water heater 23 is placed beneath the boiler C in position to receive the hot gasses of combustion from the lower grate 19, and also acts as a barrier to prevent the ashes from working back under said boiler. A water supply pipe 24 is connected to one end of the water heater and a flow or hot water pipe 25 extends from the opposite end thereof. By removing the pipes 24 and 25, the water heater may be easily removed.

The boilers B and C are connected together by the flange couplings 26 and 27, whereby water circulating means is afforded from one boiler to another. The lower boiler C is completely filled 5 with fire tubes 9, while the upper boiler B is not completely filled with fire tubes, but has a steam space 28 at the top. The lower boiler C is heated first and would ordinarily heat up much faster than the upper boiler B, but I have compensated for this by extending the circulating 10 pipe 29 from the bottom of the boiler C to the bottom of boiler B. By this arrangement, the hot water from boiler C can pass up into boiler B through the couplings 26 and 27, thus forcing 15 the cooler water from the boiler B down to the bottom of the boiler C through the circulating pipe 29.

The purpose of placing the boilers B and C one above the other, is to provide a long travel for 20 the hot gasses of combustion, which are distributed over a large heating surface in as small a space as possible. By this arrangement the stack temperature is reduced to nearly the temperature of the water in the boiler, notwithstanding 25 the fact that the perfect combustion of the fuel by the down draft through the bed of live coals creates an intense heat.

The draft space 30 formed between the fire box A and the front end of the lower boiler C, is 30 covered by a heat resisting cement that forms an arch 31. This arch rests on the upper side of the boiler C and the brick walls 1, is easily applied and forms a very tight leak proof joint. A direct draft opening 32 passes through this arch 35 and connects with the draft passage 33, allowing a generous amount of heat to enter the passage 33 and thence through the outlet 34 to the chimney. This is for the purpose of warming up the chimney by driving out the cold air and 40 quickly creating a good draft when first starting the fire.

The generated steam passes out through the pipe connection 35 at the top of the boiler B. A steel plate 36 covers the front of the passage 45 33 and may be easily removed if necessary, to repair the fire tubes 8 or other parts. This plate has an opening 37 covered by a door 38 that can be used as a check draft and also in cleaning out the passage 33.

50 In starting a fire, the entire surface of the water tube grates 16 of the combustion chamber 14 are first covered with fuel. Kindling is then placed on the coal and ignited. The draft is drawn in through the opening 39 of the fuel door 40 and enters the fuel bed with a downward movement, causing the kindling to ignite the fuel beneath. The draft continues downwardly and enters the second combustion chamber 15, and passes out of this chamber through 55 passage 41. The cast iron grates 19 of the combustion chamber 15 are spaced closer together than the water tube grates 16, for the purpose of catching the cinders or unconsumed fuel from the latter. The second draft required to cause 60 the complete combustion of the fuel, is drawn in through the opening 22 in hinged lid 21, and passes down into the ash pit 20 below the level of the floor, thence upwardly through the cinder bed of the grate 19 and out through the passage 41. Both the upper and lower drafts come 65 together and pass beneath and also through the fire tubes 9 of boiler C to draft passage 42. The draft under the boiler C passes over the water heater 23 and enters the passage 42 through the 70 opening 43 in the steel supporting plate 3, con-

tinuing up through this passage and entering the fire tubes 8 from the rear end of the boiler B. This draft then enters passage 33 and passes via the outlet 34 to the chimney.

Among the many advantages derived through 5 the use of my invention, some of the more important may be briefly enumerated as follows:

First.—The device consists of three separate units, namely, the fire box and the upper and lower fire tube boilers.

Second.—The upper fire tube boiler being mounted above the lower boiler gives a long fire travel through the fire tubes, while occupying only a small space.

Third.—The upper boiler receives all of the 15 steam generated in the lower boiler by passing through the flange pipe couplings.

Fourth.—The upper boiler receives its water supply entirely from the lower boiler.

Fifth.—The upper boiler receives all of the 20 steam generated in the fire box unit.

Sixth.—The upper boiler receives the heat that is left after passing under and through the lower boiler, since a reversed forward movement of the draft is necessary to reach the chimney.

Seventh.—The lower boiler is completely filled with fire tubes and water, and hence, no space is allowed for steam above the tubes.

Eighth.—The fire box unit and the lower boiler are built separately and secured together when installing, making it much easier to handle the several units and easy to get around and through small openings.

Ninth.—The boiler has a direct draft which makes it possible to start a quick fire, when 35 otherwise the draft would be poor.

Tenth.—My present boiler construction may be used for low pressure heating, as a high pressure power boiler or for a hot water heating 40 boiler.

Eleventh.—Any kind of fuel will burn satisfactorily.

Twelfth.—The device may be easily converted from a coal burning boiler to an oil or gas boiler.

From the foregoing description taken in connection with the drawings, it is thought that the construction, operation and advantages of my invention will be readily understood, without requiring a more extended explanation.

Various changes in the form, proportions and minor details of construction may be resorted to without departing from the principles or sacrificing any of the advantages of my invention, as defined in the appended claim.

Having described my invention, what I claim as new and desire to secure by Letters Patent, is:

A steam generator comprising upper and lower fire tube boilers, made in separate units and connected together by tubular pipe couplings, a 60 separate fire box unit situated in front of the lower boiler and comprising upper and lower combustion chambers, means for creating down and up drafts through the upper and lower combustion chambers, respectively, means for causing a reversed forward movement of the hot gasses of combustion through the upper boiler after passing under and through the lower boiler, a vertical plate having a draft opening and openings to receive the rear ends of the upper and lower boilers, an oval casing carried by said plate and a cover plate for the casing, said vertical plate, oval casing and cover plate forming a vertical passage or compartment at the rear ends of the boilers.

BRACE ALDEN PHILLIPS.
